DISCHARGE LAMP ASSEMBLY

Benjamin C. Webster, Fairfield, Conn., and Roy M. Smith, Bethlehem, Pa., assignors to The Bryant Electric Company, Bridgeport, Conn., a corporation of Connecticut

Application June 3, 1943, Serial No. 489,512

7 Claims. (Cl. 176—122)

Our invention relates, generally, to lamps or arc discharge devices and, more particularly, to an assembly of a discharge lamp of the circular or bent type, as distinguished from the straight double-ended lamps in common use, and a mounting base or holder for the lamp. Reference hereinafter to circular lamps is intended to include all such shapes as circular, oval, etc., where the tube is so bent or formed as to bring the ends in spaced facing relation.

The object of our invention, generally stated, is to provide a lamp assembly embodying a tubular discharge lamp of the circular type which shall be of simple and inexpensive construction, which may be readily attached to an external supply circuit, and which shall function to properly support and conduct current to the lamp regardless of manufacturing variations in the sizes of the lamps with respect to the diameter of the tubing and the distance or spacing between adjacent ends of the tubing.

A more specific object of our invention is to provide a base or holder for tubular discharge lamps of the circular type which may be used with a lamp which is not provided with the usual metal end caps or bases and contact pins to provide a complete lamp assembly ready for connection to an external supply circuit.

Another object of our invention is to provide a base or holder of the character described which shall embody the starting switch or relay for the lamp.

A further object of the invention is to provide a base or holder wherein the ends of the lamp are attached to a housing member by means of an adjustable band or cover element to accommodate lamps of slightly different diameters.

Another object of the invention is to provide a base or holder of the character described which is adapted for use with lamps which vary in the distance or spacing between adjacent ends.

A still further object of the invention is to provide a base or holder which may be readily attached to the lamp to provide a complete lamp assembly suitable for attachment to an external supply circuit.

In accordance with one embodiment of our invention, a housing member of insulating material is provided with seats or depressions at the ends thereof on its upper surface or face portion to receive the adjacent ends of a double-ended tubular discharge lamp of the circular type which is not provided with the usual end caps and contact pins, but instead has lead-in wires extending through the ends of the glass envelope from the

filaments. The lamp is secured to the housing member by a U-shaped retaining band of metal or the like which is positioned over the ends of the lamp and bent around the lower side edges of the housing member. The housing member is preferably provided with longitudinal slots in the bottom adjacent the bottom edges thereof into which the free ends of the U-shaped member are crimped. The open slots in the face of the housing member and the width of the retaining band are such as to accommodate lamps having varying distances between their adjacent ends. The length of the band is such that lamps of varying diameters, that is, varying diameters of the tubular envelope, may be used. The space between the ends of the lamp beneath the band is utilized to house a starting switch and condenser, the condenser being connected across the terminals of the starting switch and one lead-in wire at each end of the lamp being connected to the terminals of the starting switch, the other lead-in wires of the lamp being connected to the inner ends of a pair of contact pins mounted on the housing member which serve to connect the lamp to an external supply circuit.

25 The nature and objects of our invention will be more readily understood from the following detailed description when considered in connection with the drawing, in which:

Figure 1 is a view of a lamp assembly embodying the principal features of our invention;

Fig. 2 is a top view with reference to Figs. 1 and 4 with a portion of the retaining band or cover removed to show the relative positions of the starting switch and condenser mounted between the ends of the lamp;

Fig. 3 is a side view in elevation and partly in section taken along line III—III of Fig. 2;

Fig. 4 is a sectional view taken along the line IV—IV of Fig. 3;

40 Fig. 5 is a view similar to that of Fig. 4 but not showing the starting switch and condenser to illustrate how the housing member is used with a lamp having a smaller diameter tubing than that of Fig. 4;

45 Fig. 6 is a view showing diagrammatically the internal wiring connection of the lamp assembly.

Referring to Figure 1, the numeral 10 designates a double-ended tubular discharge lamp of the circular or bent type which is attached to a base or holder designated generally at 11 constituting a lamp assembly adapted for attachment to a supply circuit by means of a suitable socket or receptacle not shown.

As shown best in Figs. 3 and 4, the base or holder 11 comprises generally a housing member 12

and a retaining band or cover 13. It may also include a starting switch 14 and the usual condenser 15 for eliminating radio interference. The housing member 12 is preferably composed of molded insulating material and is provided with a generally flat bottom surface 16, straight or vertical side walls 17 and with its upper surface so formed as to receive the ends of the lamp and also provide for mounting the starting switch and condenser.

It will be observed that the housing member is provided on its upper surface with shallow depressions 18 at the ends thereof so shaped as to receive the ends of the lamp and also with a central recess 19 in which the starting switch 14 and condenser 15 are mounted. The housing member 12 is also provided with a pair of depending contact pins 21 which function to support the lamp assembly and connect it with an external source of supply. It is to be understood, of course, that additional support means in the form of clips or brackets, not shown, could be utilized if necessary to support the lamp assembly in use.

The lamp illustrated in this instance is one which is not provided with the usual metal end caps and contact pins, but instead, a pair of lead-in wires 22-23 and 24-25 extend through each end of the glass envelope, as shown in Fig. 2. The starting switch 14, which may be of any well known construction, is provided with a pair of terminal wires 26 and 27 which are connected with the lead-in wires 22 and 24 of the lamp as shown. The lead-in wires 23 and 25 of the lamp are connected to the contact pins 21 mounted in the housing member.

The internal circuit of the lamp assembly embodying these connections is shown better in Fig. 6 which also shows the condenser 15 connected across the terminals 26 and 27 of the starting switch. This arrangement provides the usual starting circuit for an arc discharge lamp of the fluorescent type and is adapted for connection to the supply circuit through the usual reactor or ballast device.

It will be apparent that this arrangement is particularly adapted for use with bridge or stand lamps where the only available location for the ballast is in the base of the lamp. By embodying the starting switch and condenser in the base or holder of the lamp, the external circuits are greatly simplified as only two conductors are required to connect the lamp assembly to the supply source through the ballast.

The retaining band or cover 13 is preferably U-shaped and composed of a deformable material such as metal in order that it may function effectively to secure the ends of the lamp to the housing member 12. As shown best in Figs. 4 and 5, the retaining band 13 is of such length that the free ends 31 and 32 thereof may be bent or crimped about the lower side edges of the housing member.

In order to effectively attach the retaining band 13 to the housing member 12 and provide for some adjustment to compensate for variations in the tubing diameter of the lamp, the housing member 12 is provided with a pair of slots 33 and 34 extending lengthwise thereof in its bottom surface adjacent the side edges. Fig. 4 illustrates the position of the retaining band in the case of a large diameter lamp and Fig. 5 shows the same band and housing member when used with a smaller diameter lamp. The slots 33 and 34 serve not only to provide a better attachment for the

ends of the band, but also as a storage space or reservoir for the excess length of the band when used with a smaller diameter lamp, as clearly shown in Fig. 5.

5 The width of the retaining band 13 and the length of the recesses or seats 18 in the housing member are such as to readily accommodate lamps having close or wide spacing between the adjacent ends, as shown in Fig. 3. The full lines

10 illustrate the case where a lamp has minimum spacing between its ends and the dot-dash lines illustrate a lamp having maximum spacing. It will be understood, of course, that the variation in spacing referred to and the variation in tubing 15 diameter are the usual manufacturing variations.

It will also be understood that the arrangement of the housing member and retaining band described also permits the use of lamps of different diameters, that is, the diameter of the circle of the tubing. This is achieved by the use 20 of the open recesses or seats 18 in the housing member and the adjustable retaining band.

It will be observed that the retaining band 13 not only serves to attach the lamp to the hous- 25 ing member but also functions as a cover for the starting switch and condenser mounted between the ends of the lamp. In making the assembly the lead-in wires and terminals are connected as

30 described hereinbefore and the retaining band attached to the housing member by means of a very simple crimping operation. This provides a complete lamp assembly ready for connection to the external supply circuit.

In view of the foregoing, it will be apparent 35 that I have provided a very simple and inexpensive lamp assembly. The lamp base or holder is not only simple and inexpensive in construction, but is flexible to accommodate lamps of different sizes and having manufacturing variations. It is also so constituted that the lamp assembly 40 may be effected by means of a very simple operation.

While I have shown and described a practical 45 embodiment of the invention, it is to be understood that various modifications may be made therein without departing from the principles of the invention.

We claim as our invention:

1. A holder for use with tubular discharge 50 lamps of the circular type comprising, a housing member provided at its ends on one side thereof with open seats to receive the adjacent ends of the lamp, said housing member having slots ex- 55 tending lengthwise thereof adjacent the side edges of its opposite side, and a U-shaped re- 60 taining band disposed to be attached to the housing member over the ends of the lamp by crimping the ends thereof into said slots to secure the lamp to the housing member.

2. A holder for use with tubular lamps of the 65 circular type comprising, a housing member formed of insulating material and having open seats in the ends on one side thereof to receive the adjacent ends of the lamp, said housing member having a depression in said side intermediate the inner ends of the open seats, a starting switch for the lamp mounted in said depression, said starting switch having terminal leads for connection to one of the terminals at each end of the lamp, a pair of contact pins mounted in the housing member, said contact pins being disposed for connection to the other terminal lead at each end of the lamp, and a U-shaped metallic retaining band for securing the ends of the lamp to the housing member by crimping the

ends of the band about the longitudinal edges of the opposite side thereof.

3. The combination of a double-ended tubular discharge lamp of the circular type having its ends in facing spaced relation, a housing member having an open seat at each end on one side thereof to receive the ends of the lamp, a pair of contact pins mounted on the housing member and extending from the opposite side thereof, and a U-shaped band member of deformable material disposed over the ends of the lamp and crimped about the longitudinal edges of said opposite side of the housing member for securing the lamp thereto, said housing member and cooperating U-shaped band member functioning as a socket or holder for the lamp.

4. The combination of a double-ended tubular discharge lamp of the circular type having its ends in facing spaced relation, a housing member having an open seat at each end in one side thereof to receive the ends of the lamp, said housing member having a slot extending lengthwise along each edge in the opposite side thereof, a pair of contact pins mounted in the housing member and extending on the opposite side thereof, and a U-shaped metallic band positioned over the ends of the lamp and having its ends bent around the edges of said opposite side of the housing member into the lengthwise slots to securely attach the ends of the lamp to the housing member regardless of slight variations in the diameter of the lamp tube.

5. The combination with a double-ended tubular discharge lamp of the circular type having a pair of lead terminals at each end, of a housing member having downwardly sloping seats in one side thereof at each end on one side thereof to receive the ends of the lamp and a depression in the surface of said one side between the seats, a starting switch for the lamp and a condenser mounted in said depression between the ends of the lamp, said starting switch having a pair of lead terminals, a pair of contact pins mounted in the housing member and extending out the opposite side thereof, said contact pins being connected to one lead terminal at each end of the lamp and said lead terminals of the starting switch being connected to the other lead terminals of the lamp and said condenser being connected across the lead terminals of the starting

switch, and a U-shaped metallic band positioned over the ends of the lamp with its ends crimped around the edges of the said opposite side of the housing member, thereby to securely attach the lamp to the housing member and provide a cover for the starting switch and condenser.

6. A holder for a tubular discharge lamp of the circular or bent type having the ends of its envelope disposed in adjacent spaced apart and facing relation comprising, a housing member shaped on one side surface thereof to receive the adjacent ends of the lamp envelope, a plurality of contact pins extending from the housing for connecting the terminals of the lamp to a current source, and a U-shaped retaining band of deformable material adapted to be positioned over the adjacent ends of the lamp envelope for securing it to the housing member by crimping the free ends of the retaining band around the longitudinal edges of the opposite side surface of the housing member, said retaining band being of such width as to accommodate lamps with varying spacing between the adjacent ends of their envelopes and of such length as to provide for securing lamp envelopes of varying diameter to the housing member.

7. The combination with a double-ended tubular discharge lamp of the circular type having a pair of filament lead-in wires extending from each end thereof, of a holder for the lamp comprising a housing member shaped on one side surface to receive the adjacent ends of the lamp, said housing member having a longitudinal slot adjacent each side edge in the opposite side surface thereof, a plurality of contact pins extending from the housing member, a U-shaped metallic retaining band positioned over the ends of the lamp and having its free ends bent around the housing member into said longitudinal slots to secure the lamp thereto, means connecting the contact pins of the housing member to one of the filament lead-in wires at each end of the lamp, and a starting switch mounted on the housing member between the adjacent ends of the lamp, said starting switch having terminal wires connected to the other filament lead-in wires of the lamp.
